STOP MOTION FOR AXMINSTER LOOMS

Walter Y. Robb, Whitinsville, Mass., assignor to
 Crompton & Knowles Loom Works, Worcester,
 Mass., a corporation of Massachusetts

Application May 29, 1947, Serial No. 751,243

12 Claims. (Cl. 139—336)

1

This invention relates to Axminster looms and it is the general object of the invention to provide means for stopping the loom if a tube frame falls from the transporting chains.

Axminster looms operate with a series of tube frames which are moved one by one to a transfer station for removal from and subsequent attachment to the chains incident to tuft forming operations. It occasionally happens that the tube frame will fail to register correctly with the transporting chain when being returned thereto, or one or another of the hooks which support the tube frame may break. Under these conditions the tube frame will fall on the cloth and interfere with the lay and the tuft cutting knives. It is an important object of the present invention to provide electric means controlled by a beam of light which will be intercepted by a falling tube frame to effect loom stoppage.

When the tube frames are removed from the chains in normal operations they will intercept the beam of light twice, once while moving downwardly toward tuft forming position, and again when returned to the chains. Since these interceptions occur regularly it is necessary to prevent them from stopping the loom. It is another object of the present invention to provide photoelectrically controlled stop means in conjunction with a switch or the like which will come into action during those intervals of tube frame movement when the latter normally intercepts the beam of light to insure continued loom running.

It occasionally happens that only one end of the tube frame will be correctly attached to the transporting chain, in which event the other end will fall to an improper position. In order to effect loom stoppage under this condition it is another object of the invention to employ two beams of light, one for each end of the loom, effective to stop the loom if either beam is intercepted at any time other than the normal intervals of interception.

With these and other objects in view which will appear as the description proceeds, my invention resides in the combination and arrangement of parts hereinafter described and set forth.

In the accompanying drawings, wherein two forms of the invention are set forth,

Fig. 1 is a side elevation of the forward part of an Axminster loom having the preferred form of the invention applied thereto.

Fig. 2 is a front elevation looking in the direction of arrow 2, Fig. 1.

Fig. 3 is a diagrammatic view illustrating the

2

manner in which one end of the tube frame may fall when its other end is attached to the chain.

Fig. 4 is a diagrammatic view of the preferred form of the electric circuit wherein the solenoid for effecting loom stoppage is normally deenergized.

Fig. 5 is a diagram of a modified circuit to be used in conjunction with the greater part of the circuit shown in Fig. 4, but wherein the solenoid is normally energized, and

Fig. 6 is a diagram of an alternate location for the control cam.

Referring particularly to Figs. 1 and 2, the loom frame 10 supports a bottom or cam shaft 11 geared to a motor M. The lay 12 reciprocates in usual manner to beat up weft in the warp shed formed by the warp threads W. The loom has a chain pullover shaft 15 operated in the usual manner by mechanism not shown to advance 20 transporting chains 16 step by step. The chain has attached thereto a plurality of tube frames 17 which move one by one to a transfer station directly under the pullover shaft 15. Tube frame transfer arms 18 disconnect the tube frame in 25 transfer position from the transporting chain system and move it downwardly toward the cloth C for a tuft forming operation. The tube frame is then moved upwardly a short distance and front and back tuft cutting knives 19 and 20 cut 30 the formed tufts from the tube frame. The latter is then returned to the chain which is then moved another step so that the next tube frame can be moved to the transfer station.

The operation just described is that occurring 35 normally when the tube frame can be detached from and reattached to the transporting chains without mishap. If, however, the tube frame should fail to be correctly attached to the transporting chains part or all of it will fall when released by arms 18. One condition which can result from improper operation of the tube frame is shown in Fig. 3, where the right end is shown as having fallen to an improper position while the left end is held by the associated chain 16. If 40 both ends fail to be attached the tube frame will fall on the cloth between knives 19 and 20. It may also happen that a tube frame which has been returned to both chains will fall due to breakage of the holding hooks as the pullover shaft turns. Under any of these or similar conditions it is highly desirable to be able to stop the loom promptly.

In carrying the present invention into effect I provide each side of the loom with a photoelectric unit so placed that its beam of light will

3

be intercepted by a tube frame moving normally from the chain to tuft forming position and then back to the chain, and also be intercepted by a tube frame which falls from the chain 16. The back knife 20 is mounted on a bar 21 which slides on stationary guides one of which is shown at 22 in Fig. 1. At each side of the loom I provide a stationary support 23, preferably secured to the loom arch 24. Right and left photoelectric tubes or cells 25 and 26, respectively, are mounted on the supports, and the loom frame supports right and left electric lamps or light sources 27 and 28, respectively, one for each cell. The beams of light between corresponding cells and sources may be substantially horizontal and are maintained throughout loom operation.

It will be understood from Fig. 1 and the description previously given that for each tuft forming operation of the loom the beams of light will normally be intercepted twice, and to prevent improper stoppage during these periods or intervals of interception provision must be made to permit continued running of the loom. This result is accomplished by a cam 30 preferably secured to the bottom shaft and turning in time with the mechanism which operates the transfer arms 18. The cam has two points 31 and 32 between which are located low dwells 33 and 34. If the loom is of the so-called three-shot type there will be a tuft forming operation every third beat-up of the lay 12, and shaft 11 and cam 30 will complete a rotation every third pick.

The electric connections for the preferred form of the invention are shown in Fig. 4 and include a loom controlling solenoid circuit and photoelectric circuit means for the solenoid circuit. The latter circuit includes a motor controlling solenoid 35 which is normally deenergized but when energized is effective to stop the motor M by well known means not shown. This circuit includes the secondary 36 of a transformer T, and two switches, switch 37 being normally open but closeable by a relay 38 when the latter is energized, and the second switch 39 being normally closed but under control of the cam 30 in such manner as to be opened twice for each tuft forming cycle by the cam points 31 and 32. Whenever both switches 37 and 39 are closed solenoid 35 will be energized to effect loom stoppage.

The circuit shown in Fig. 4 includes the two photoelectric cells 25 and 26, a transformer T', and an electronic gas filled tube E having a plate 40, control grid 41, grounded cathode 42, and cathode heating filament 43. The latter is energized by secondary winding 44 of transformer T', and plate 40 is connected to one side of the relay 38. The other side of the relay is connected to one side of secondary 45 the other side of which is grounded. Section 46 of secondary 45 supplies power for operation of the photoelectrically controlled part of the circuit shown at the right of Fig. 4. This part of the circuit includes a variable resistor R and resistances R' and R₂ connected as indicated in Fig. 4. The two photoelectric cells or tubes are in parallel and connected across wires 48 and 49, the latter being connected through a resistance 50 to the grid 41. Condensers 52 and 53 are employed as indicated.

The source of light 27 and 28 are supplied with electric power from the secondary 36, and are constantly illuminated. So long as the cells 25 and 26 are energized by light the grid 41 is maintained sufficiently negative to prevent firing of tube E. Whenever one or the other or both tubes 25 and 26 fail to receive light the grid 41 becomes

4

sufficiently positive to permit firing of tube E to energize the relay 38.

It will be understood that the cells 25 and 26 will normally be inactivated or un-illuminated twice for each normal tuft forming operation of a tube frame. During the two periods of normal interception of the beams of light tube E will fire, thereby closing switch 37. Cam 30, however, operates in such manner that during these periods of light interruption its points 31 and 32 will open switch 39, thereby preventing energization of solenoid 35 which would otherwise ensue upon closure of switch 37. As soon as the tube frame in its normal operation moves away from the beams of light one or another of the dwells 33 or 34 will permit closure of switch 39. The result of this relationship is to permit closure of the solenoid circuit upon energization of relay 38 at any time in the cycle of the loom other than the intervals during which the beams of light are normally intercepted.

If, for instance, the tube frame has completed a tuft forming operation and has been returned to high position and released by the transfer arms 18, it may be that one end of the tube frame will fall across the corresponding beam of light, thus energizing relay 38, but at this time switch 39 will be closed due to the position of cam 30, and solenoid 35 will therefore act to stop the motor M. A similar condition will exist if the tube frame should happen to fall across a beam of light at any time other than the intervals corresponding to the cam points 31 and 32.

In the modified form of the invention a solenoid 69 similar to solenoid 35 is normally energized and its deenergization effects motor stoppage by well known means not shown. In this form of the invention the transformer secondary 36 has one side thereof connected to switches 61 and 62 similar to switches 37 and 39, respectively. Switch 61 is normally in the closed position shown in Fig. 5 while cells 25 and 26 are activated by light, and relay 38 is dead. Switch 61 will, however, be opened twice for each tuft forming cycle when relay 38 is energized by inactivation of the photocells as the tube frames cross the beams of light. Switch 62 is normally open but is closed by the cam points 31 and 32 when relay 38 is normally energized.

Under normal operations therefore secondary 36 will be able to maintain uninterrupted energization of solenoid 60 to permit continued running of the loom, since switch 62 will be closed by the cam when switch 61 is open. If a tube frame should fall with resultant energization of relay 38 while switch 62 is open the resultant opening of switch 61 will deenergize solenoid 60 to effect motor stoppage.

Cam 30 has been described as controlling the solenoid circuit, but if desired it can be used to control the relay circuit instead. Thus, in Fig. 6 a switch 65 in the relay circuit is normally closed but is opened momentarily by cam 30 whenever the tube frame intercepts the beams of light.

From the foregoing it will be seen that I have provided means for stopping an Axminster loom in the event that a tube frame falls out of the chains 16. This result is obtained whether both ends or only one end of the tube frame falls, since a shadow on either cell 25 or 26 will change the condition of the control grid. Also, the photoelectric cells can be used in conjunction with a loom controlling solenoid which is either normally deenergized or normally energized.

The cam 30 acts to maintain normal conditions when the beams of light are regularly intercepted during normal movements of the tube frame incident to a tuft forming operation. If a tube frame should intercept either or both beams of light at any time other than the normal periods for interception a change will occur in the energization of relay 38 and solenoid 35 or 60 to effect loom stoppage.

Having thus described my invention it will be seen that changes and modifications may be made therein by those skilled in the art without departing from the spirit and scope of the invention and I do not wish to be limited to the details herein disclosed, but what I claim is:

1. In an Axminster loom operating with a transporting system from which tube frames are removed one at a time during tuft forming intervals, a photoelectric cell, a source of light providing a beam of light normally illuminating said cell, and electric means controlled by said cell effective when said beam is intercepted by a tube frame falling from a portion of said system at any time other than during a tuft forming interval to initiate loom stoppage.

2. In an Axminster loom operating with tube frames on a transporting system, a photoelectric cell, means providing a beam of light for illuminating the cell, said beam located in position to be intercepted by a tube frame improperly falling from a portion of the system and out of control of the loom, an electromagnetic device effective upon a change in the magnetic field thereof to initiate loom stoppage, an electric circuit operative upon a change from normal to abnormal condition thereof to cause said change in the field of said device, and electric circuit means controlled by said photoelectric cell and effective upon a change in the illumination of said cell due to a falling tube frame out of control of the loom to change the condition of said electric circuit from normal to abnormal and thereby cause a change in the magnetic field of said device.

3. In an Axminster loom operating with tube frames which move one by one from a transfer station to tuft forming position and then return to the transfer station, electric loom stopping means effective upon an electric change therein to cause loom stoppage, a photoelectric cell normally illuminated by a beam of light which is intercepted at regularly recurring intervals by a tube frame moving normally toward and away from tuft forming position, electric control circuit means controlled by said cell normally tending to cause an electric change in said electric stopping means whenever the beam of light is intercepted by a tube frame, and means effective during said intervals only to prevent an electric change in said electric stopping means.

4. In an Axminster loom operating with tube frames which move one by one from a transfer station to tuft forming position and then return to the transfer station, stopping electric circuit means including an electromagnetic device effective upon a change in the magnetic field thereof due to an electric change in said circuit means to cause loom stoppage, a photoelectric cell, a source of light providing a light beam normally falling on said cell, a tube frame when moving normally toward and away from tuft forming position intercepting said light beam at regularly recurring intervals, control electric circuit means for said stopping circuit means controlled by the cell and normally tending whenever said

light beam is intercepted to cause an electric change in said stopping circuit means and said magnetic field, and means to prevent an electric change in said stopping circuit means field during said intervals only.

5. In an Axminster loom operating with a tube frame having a period of movement toward and away from tuft forming position, an electromagnetic device effective upon a change in the magnetic field thereof to cause loom stoppage, electric circuit means which when altered electrically changes said magnetic field, and two controls for the electric circuit means, one control including a photoelectric cell the illumination of which is interrupted at given intervals during said period of movement of the tube frame, said one control tending whenever the illumination of said cell is interrupted during said period to alter the electric circuit means to cause a change in said magnetic field, and the other control acting during said intervals only to prevent electric alteration of said electric circuit means.

6. In an Axminster loom operating with tube frames which have normal movements one by one from a transfer station to tuft forming position and then back to transfer station, an electromagnetic device effective upon a change in the magnetic field thereof to cause loom stoppage, electric circuit means which when altered electrically causes a change in said magnetic field, and two controls for the electric circuit means, one control including a normally illuminated photoelectric cell and tending whenever the illumination of the cell is interrupted by a tube frame to alter the electric circuit means to cause said change in said magnetic field, and the other control acting periodically in timed relation with said normal movements of a tube frame to prevent the first control from altering said electric circuit means.

7. In an Axminster loom operating with tube frames which normally move one by one toward and away from tuft forming position, stopping electric means including an electromagnetic device effective upon alternation of the electric condition thereof to change the magnetic field of said device to cause loom stoppage, a photoelectric cell adjacent to each end of the tube frame, light source means providing two beams of light, one for the illumination of each cell, which are intercepted at regularly recurring intervals by a tube frame moving normally toward and away from tuft forming position, electric circuit means controlled by both cells tending normally to cause alteration of said stopping electric means whenever either beam of light is intercepted by a tube frame, and means effective during said intervals only to prevent said electric circuit means from altering the electric condition of said stopping electric means.

8. In an Axminster loom operating with tube frames which normally move one by one toward and away from tuft forming position, an electromagnetic device effective upon a change in the magnetic field thereof to cause loom stoppage, a photoelectric cell, light source means providing a beam of light normally illuminating said cell, said beam of light being interrupted at regularly recurring intervals by a tube frame moving normally toward and away from tuft forming position, electric circuit means controlled by said cell tending normally to cause alteration

of said magnetic field whenever the beam of light is intercepted by a tube frame, and means effective during said intervals only to prevent said electric circuit means from causing alteration of said magnetic field.

9. In an Axminster loom operating with a tube frame which has a normal movement toward and from tuft forming position, an electromagnetic device effective upon a change in the magnetic field thereof to cause loom stoppage, electric circuit means normally maintaining said field unchanged but effective upon electric alteration thereof to cause said change in said field, and two controls for the electric circuit means, one control comprising photoelectrically acting means including a beam of light and tending to alter the electric circuit means to effect a change in said field whenever said beam of light is intercepted during said movement of the tube frame, said tube frame intercepting said beam during a given interval in said normal movement thereof, and the other control including a cam operated switch moving in time with the tube frame during said normal movement thereof and effective to prevent the first control from altering said electric circuit means during said interval.

10. In an Axminster loom operating with tube frames which one by one have regular movements toward and away from tuft forming position, an electromagnetic device effective upon a change in the magnetic field thereof to cause loom stoppage, electric circuit means effective upon alteration thereof to cause said change in said field, a relay controlling said electric circuit means, a switch also controlling said electric circuit means, photoelectric means including a photoelectric cell energized by a beam of light effective when said beam of light is intercepted to cause said relay

to alter said electric circuit means for the purpose of altering said field, a tube frame when having said regular movements intercepting said beam of light at given intervals, and a member moving in timed relation with a tube frame having said regular movements acting on said switch during said given intervals only to prevent said relay from altering said circuit means.

11. In an Axminster loom operating with tube frames which normally intercept a beam of light at regularly recurring intervals during normal loom operation, a photoelectric cell normally illuminated by said beam of light, normally open electric circuit means including an electromagnetic device which is energized only when said circuit means is closed and when energized initiates loom stoppage, a second electric circuit means controlled by said cell and effective when said beam of light is intercepted to close the first electric circuit means, and means operative during said intervals only to maintain the first circuit means open.

12. In an Axminster loom operating with tube frames which normally intercept a beam of light at regularly recurring intervals during normal loom operation, a photoelectric cell normally illuminated by said beam of light, normally closed electric circuit means including an electromagnetic device energized when the circuit means is closed but effective upon deenergization thereof due to opening of said circuit means to initiate loom stoppage, a second electric circuit means controlled by said cell and effective upon interception of said beam of light to open the first circuit means, and means operative to maintain the first circuit means closed during said intervals only.

WALTER Y. ROBB.
